ROOF CONSTRUCTION

Filed Sept. 12, 1931

UNITED STATES PATENT OFFICE

2,005,533

ROOF CONSTRUCTION

Paul Chapman, New York, N. Y.

Application September 12, 1931, Serial No. 562,535

10 Claims. (Cl. 108—1)

This invention in roof construction provides an economical supporting construction for the outside roof covering of a peaked roof, and an unobstructed space beneath the roof for lighting 5 and ventilation.

Referring to the accompanying drawing, Fig. 1 is a perspective view of one of the hip rafters. Fig. 2 is an elevational view of the same. Fig. 3 is a plan view showing the means of adjusting the 10 end of the said rafter horizontally. Fig. 4 is an elevational view showing the means of horizontal adjustment when the construction is adapted to structures having supporting masonry wall enclosures. Fig. 5 is an elevational view of one of the 15 hip rafters when the said rafter is bent between the peak and the eaves to conform to the outline of the roof or for any other reason. Fig. 6 is a plan view of the construction adapted to an approximately square or rectangular shaped 20 roof. Fig. 7 is a plan view of the construction adapted to an irregular shaped roof having eight of the aforesaid hip rafters. Fig. 8 is a plan view of the construction adapted to a roof of rectangular form having one side much longer than 25 the other.

Referring to Figs. 1, 6, 7, and 8; a structural hip rafter 1 extends diagonally downward from a peak member 2 to a vertical support 3. Jack rafters 4a 4b upon which the roof covering rests 30 are supported at their upper ends by the hip rafter. Strut members 5a 5b 5c support the lower ends of the jack rafters 4b and the upper ends of the rafters 6a 6b, and are themselves supported at their ends by the hip rafters 1. The lower ends of the rafters 6a 6b rest upon 35 the eave members 1a 1b 1c 1d 1e 1f. Referring to Fig. 2, L shaped members 1a support the ends of the strut members 5a and also resist the compression in the bottom flanges of the 40 strut members at their ends. The axes of the bottom flanges of the struts 5a intersect the axis of the rafter 1 as near to its bottom flange as practical, and a resultant upward reaction and a diagonal compression in the rafter 1 near and 45 parallel to the bottom flange results from the compression in the strut members 5a. The compression along the bottom flange of the rafter is transferred thru the member 1b and is resolved into a vertical reaction in the support 30 (Fig. 1) and tension in both of the diagonally intersecting members 1a (Fig. 1). By 50 constructively locating the compressive stresses in the rafter 1 and the struts 5a along their bottom flanges, negative bending moments are produced 55 which reduce the positive bending moments due

to their vertical loads and result in economy of material. The upper end of the rafter 1 is connected to the peak member 2 by a connection piece 1c rigidly connected to the rafter and bolted to the piece 2. The ends of the rafter 1 are reduced in depth to clear other parts and strengthened by cutting wedge shaped pieces from the ends of the web and then bending the top flange downward and welding to the bottom portions along the lines 1d and 1e.

When the construction is loaded, the bottom flange of the rafter 1 tends to describe a slight convex arc due to the elastic deformation of the stressed members. This condition is compensated for by either increasing the length of the 10 struts 5a from their normal lengths and decreasing the lengths of the members 1a likewise to allow for deformation, and drawing the top ends of the rafters 1 against the peak pieces 2 by means of the bolts 2a fitting into holes in the said peak pieces; or by forcing the lower end of the rafter inward by the use of the U shaped bolts 7g with threaded nuts 7h forced against angles 7k rigidly attached to the diagonally intersecting members 1a, as shown in Fig. 3. 25

Referring to Fig. 4, the construction is adapted to masonry wall support, and the ends of the rafters 1 rest upon and are rigidly attached to plates 7m loosely held in position on top of the wall 3a by anchor bolts 3b with threaded nuts 30 and washers extending thru holes in the plates 7m of a size sufficient for the required movement. Rods 7n extending between the adjacent plates 7m under the ends of the adjacent rafters 1, have threaded nuts 7o at their ends which are forced against structural angles 7r rigidly attached to the plates 7m in order to force the ends of the rafters 1 inward horizontally. This method also compensates for the deflection of the rafter 1 when the structure is loaded. 40

Referring to Fig. 5, where on account of its bent shape the rafter 1 is built up of a plate 1f and two top angles 1g and two bottom angles 1h, the same methods of compensating for deflection are used as described heretofore. 45

Referring to Fig. 6, by the methods of compensation heretofore described, a compression rectangle is formed by the four struts 5a, a tension rectangle by the four eave members 1a, the lower portions of the rafters 1 form compression members connecting the apices of the said rectangles, and the amount of stress in the peak member 2 can be regulated for economic or other reasons. 50

Referring to Fig. 7, by the same methods, a compression polygon is formed by the struts 5a 55

5c, a tension polygon by the eave members 1c 7d
 7e 7f 7s, the lower portion of the rafters 1 form
 compression members connecting the apices of
 the said polygons, and the amount of stress in the
 5 peak member 2 can be regulated. An additional
 polygon is formed by the members 5d 5e connecting
 the rafters 1 horizontally between the connec-
 tions of the struts 5a 5c and the peak 2. This
 10 adaptation of the construction is suitable for
 roofs covering large areas.

Referring to Fig. 8, by the same methods as
 heretofore, a compression rectangle is formed by
 the struts 5a 5b, a tension rectangle by the eave
 15 members 7a 7b, the lower portions of the rafters
 1 form compression members connecting the
 apices of the said rectangles, and the amount of
 stress in the two peak members 2 can be regu-
 lated. An additional horizontal member 2b fix-
 20 edly connecting the peak members 2 transfers the
 horizontal stress transferred into the peak mem-
 bers 2 by the rafters 1. When the loads carried
 by the construction are unsymmetrical about the
 short axis of the rectangular roof, members 2c
 25 rigidly connecting the peak members 2 with the
 strut 5b, transfer vertical reactions between the
 peak members.

Referring to Fig. 6, the procedure in designing
 is hereafter outlined. The vertical deflection of
 30 the point of intersection of the strut members 5a
 with the hip rafters 1, is calculated for the two
 systems of supporting members by first consid-
 ering the peak member 2 loosely connected and
 the strut members 5a in compression, and then
 35 next by considering the strut members 5a to
 transfer shear only to the hip rafters 1. The por-
 tion of the total load supported by each system
 is inversely proportional to the deflections thus
 found, provided that all the stressed members
 40 are of normal lengths. The first system produces
 a negative bending moment in the hip rafter 1
 whereas the second system produces a positive
 moment, so that the resultant moment for which
 the hip rafter is designed becomes smaller, with
 45 resultant economy. A further possible economy
 may result by making a normal gap between the
 ends of the hip rafters 1 and the peak member 2,
 and then forcing these members together by
 50 tightening the bolts 2a Fig. 2, which operation
 increases the negative bending moment in the
 hip rafters 1. If desired, instead of the foregoing,
 a positive bending moment in hip rafters 1 may
 be added by making the hip rafters 1 longer than
 55 normal so that the peak member 2 must be forced
 into position by loosening the bolts 1g Fig. 3.
 The stresses produced by either of the foregoing
 operations are calculated by multiplying the
 60 stresses caused by a unity horizontal load applied
 at the peak member 2, by the ratio of the hori-
 zontal displacement occurring in the operations to
 that of the unity load, the peak member being
 assumed to be loosely connected.

An adaptation of my invention referred to in
 Fig. 6 follows. The members 5a are increased in
 65 length and 7a decreased to compensate for stress
 deformation, so that under full dead load the
 member 2 loosely fits in place. Negative bending
 moments then exist in the members 1 where the
 members 5a connect, and after the member 2 is
 70 rigidly attached, the positive moments from the
 live load cancel a portion or all of the negative
 moments. The bending moments are the major
 factors in designing the members 1, and my inven-
 tion affords a skilful designer an opportunity to
 75 effect great economies.

I claim:

1. In roof construction, a peaked four-sided
 framework supporting a roof, four hip-rafters ex-
 5 tends from the peak to the eave-corners of the
 said framework, four eave-members forming the
 perimeter of the said framework, four compres-
 sion struts with their ends rigidly attached to
 the said hip-rafters and forming a compression
 10 quadrilateral between the eaves and peak of the
 said framework, a peak member connecting the
 four said hip-rafters together.

2. In roof construction, a peak-ridged four-
 sided framework supporting a roof, four hip-rafters
 15 extending in pairs from each end of the peak-
 ridge to the eave-corners of the said framework,
 four eave-members forming the perimeter of the
 said framework, four compression struts with
 their ends rigidly attached to the said hip-rafters
 and forming a compression quadrilateral located
 20 between the eaves and peak-ridge of the said
 framework, a horizontal peak-ridge member con-
 necting the top ends of the two pairs of said hip-
 rafters, diagonal members in the plane of the
 roof attached at one end to the said peak-ridge
 25 member and at the other end to one of the said
 compression struts, the said diagonal members
 providing means for transferring vertical loads
 from one end of the peak-ridge member to the
 other, substantially as described.

3. In roof construction, a peaked plural-sided
 framework supporting a roof, plural hip-rafters
 each extending from the peak to one of the eave-
 30 corners of the said framework, plural eave-members
 forming the perimeter of the said frame-
 work, compression struts with their ends at-
 tached to the said hip-rafters consecutively
 and forming a compression polygon located
 35 between the peak and eaves of the said frame-
 work, a peak member connecting the top ends
 of the said hip-rafters together all the fore-
 going members being means to support the roof
 by the combined action of the said hip-rafters
 40 and the said compression struts substantially as
 described.

4. In roof construction, a peaked plural-sided
 framework supporting a roof, with a polygon-
 shaped ridge extending around the said roof be-
 45 tween the peak and the eaves, plural hip-rafters
 bent to conform to the said ridge and extending
 from the peak to the eaves of the said framework,
 compression struts with their ends attached to
 the said hip-rafters consecutively and forming a
 50 compression polygon located substantially at the
 said ridge, a peak member connecting the top
 ends of the said hip-rafters together plural eave
 members forming the perimeter of the said frame-
 work, all the foregoing members being
 55 means to support the roof by the combined ac-
 tion of the said bent hip-rafters and the said
 compression struts substantially as described.

5. In roof construction, a peaked plural-sided
 framework supporting a roof, plural hip-rafters
 each extending from the eaves to the peak of the
 said framework, compression struts with their
 ends attached to the said hip-rafters consecu-
 65 tively and forming a compression polygon located
 between the peak and eaves of the said frame-
 work, a peak member connecting the top ends of
 the said hip-rafters together, eave-members
 forming the perimeter of the said framework,
 70 bolts with adjustable screw-threaded nuts at-
 taching the said hip-rafters to the said peak
 member, the said bolts being means of com-
 pensating for the deflection of the said hip-raft-
 ers under applied loads and to apportion stresses

carried by the said compression struts and the said peak member, substantially as described.

6. In roof construction, a peaked plural-sided framework supporting a roof, plural hip-rafter 5 each extending from the peak to the eaves of the said framework, compression struts with their ends attached to the said hip-rafters consecutively and forming a compression polygon located between the peak and eaves of the said 10 framework, a peak member connecting the top ends of the said hip-rafters together, eave members forming the perimeter of the said framework, connection pieces attaching the said compression struts to the said hip-rafters through 15 the bottom flanges of the said compression struts and directing the compressive force along the bottom flanges of the said compression struts to compensate for the bending moments in the compression struts under applied loads, the said 20 connection pieces being means to reduce the deflections and the amount of material necessary for the construction of the said compression struts, substantially as described.

7. In roof construction, a peaked plural-sided framework supporting a roof, plural hip-rafter 25 each extending from the peak to the eaves of the said framework, compression struts with their ends attached to the said hip-rafters consecutively and forming a compression polygon located 30 between the peak and the eaves of the said framework, a peak member connecting the top ends of the said hip rafters together, eave members forming the perimeter of the said framework, connection pieces attaching the said compression struts to the said hip-rafters near the 35 bottom flanges of the said hip-rafters and connection pieces attaching the bottom flange of the said hip-rafters to the said eave members in order to direct the compressive forces along the bottom flanges of the said hip-rafters and reduce the 40 bending moment in the hip-rafters from the applied loads, the location of the said connection

pieces providing means to reduce the deflection and the amount of material necessary for the construction of the said hip-rafters, substantially as described.

8. In roof construction, a peaked plural-sided framework supporting a roof, plural hip-rafters each extending from the peak to the eaves of the said framework, a peak member connecting the top ends of the said hip-rafters together, eave members forming the perimeter of the said framework, compression struts with their ends attached consecutively to the said hip-rafters and forming plural compression polygons at desired levels located between the peak and the eaves of the said framework, a tension polygon 15 formed by the said eave members at the eave level.

9. In roof construction, a peaked plural-sided plural-ridged framework supporting a roof, plural hip-rafters bent to conform to the plural 20 ridges of the said framework and extending from the peak to the eaves of the said framework, compression struts with their ends attached consecutively to the said hip-rafters and forming plural compression polygons substantially 25 at the levels of the said ridges, a peak member connecting the top ends of the said hip-rafters together, eave members of the said framework forming a tension polygon at the eave level.

10. In roof construction, a peaked plural-sided framework supporting a roof, plural hip-rafters extending from the peak to the eaves of said framework, a peak member connecting the said hip-rafters together, compression struts with 30 ends attached to the said hip-rafters and forming polygons between the peak and eaves, and means to fix the proportionate load carried by the peak member and the compression struts by compensating for stress deformation substantially 35 as described.
